CLAIM

The ornamental design for a broom, as shown and described.

DESCRIPTION

FIG. 1 is a top, front, right perspective view of a broom showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a top, rear, left perspective view thereof.

The uneven-length broken lines represent boundaries of the claimed design and form no part of the claimed design. The

(Continued)

even-length broken lines represent portions of the broom that form no part of the claimed design.
